UNITED STATES PATENT OFFICE.

ALFRED ARTHUR GODFREY, OF STAINES, ENGLAND.

MANUFACTURE OF LINOLEUM.

No. 835,518.

Specification of Letters Patent.

Patented Nov. 13, 1906.

Application filed August 30, 1906. Serial No. 332,688.

To all whom it may concern:

Be it known that I, ALFRED ARTHUR GODFREY, engineer, of The Linoleum Manufacturing Company Limited, a subject of the 5 King of Great Britain, residing at Staines, in the county of Middlesex, England, have invented certain new and useful Improvements in the Manufacture of Linoleum, of which the following is a specification.

The object of this invention is to obtain linoleum with a wood-like appearance. To do this, I form coils of a thin ribbon made of linoleum material of two colors, and I introduce these coils edgewise to a pair of rolls—that is, the axis of each coil is approximately 15 perpendicular to the axes of the rolls. Preferably the ribbon is formed of dark and light colored material, so that the one side of the ribbon is darker than the other. This may be done by feeding the material from two hopper-mouths close to the nip of a pair of rolls or from a single hopper divided into two compartments by a thin plate extending down close to the mouth. The sheet so formed may be cut by a series of knives into 25 a number of ribbons, or the sheet may be rolled up into a roll, which is then cut up into coils, the cuts being perpendicular to the axis of the roll or inclined thereto. The coils 30 either formed of ribbons or cut from a roll are then rolled out thin, and the squeezing action of the rolls causes the light and dark material to appear on the face of the sheet so formed, and an excellent imitation of wood-grain is thus obtained.

Preferably the coils are formed on a mandrel which can be withdrawn from them, and they are then flattened before passing through the rolls.

Figures 1 and 2 are a section and plan of a machine for forming the coils. Figs. 3 and 4 are a section and plan of the machine for rolling out the coils. Figs. 5 and 6 are a cross-section of a coil formed on a mandrel before and after flattening.

45 *a* is a hopper with a central partition *b*, delivering light and dark linoleum material to the nip of a pair of rolls *c*, by which a sheet of linoleum dark on one side and light on the other can be formed. This sheet is cut by a

series of knives *d* beneath one of the rolls *c* into a number of ribbons which are coiled into a number of coils *e*.

The coils are introduced edgewise between a roll *f* and guide-rolls *g*, by which they are 55 fed to the nip between the roll *f* and a similar roll *h*, by which they are amalgamated together and rolled out into a sheet, as clearly shown in the drawings. The coils are of course packed as closely together as possible, 60 half-coils being used where necessary. A somewhat superior effect is obtained by coiling the ribbons on a mandrel, as shown in Fig. 5. After withdrawing the mandrel the coils are then squeezed flat, as shown in Fig. 6, before being introduced into the second machine, the squeezing action of which imparts the wood-like appearance to the finished sheet.

What I claim is—

1. The process of manufacturing linoleum which consists in forming coils of a thin ribbon of linoleum material introducing the coils edgewise to a pair of rolls and rolling out the coils substantially as described.

2. The process of manufacturing linoleum which consists in cutting up into ribbons a sheet formed of linoleum material of two colors forming the ribbons into coils, introducing the coils edgewise to a pair of rolls 80 and rolling out the coils substantially as described.

3. The process of manufacturing linoleum which consists in cutting up into ribbons a sheet formed of linoleum material of two colors forming the ribbons into coils on a mandrel, withdrawing the mandrel from the coils, squeezing them flat, introducing the coils edgewise to a pair of rolls and rolling out the coils substantially as described.

4. A sheet of linoleum composed of a number of coils consolidated together by rolls to which they are introduced edgewise, the coils being formed of a thin ribbon of linoleum material substantially as described.

ALFRED ARTHUR GODFREY.
